(57) **CLAIM**

The ornamental design for a two-part quick coupling device for electronic game steering wheels, as shown and described.

DESCRIPTION

The patent or application file contains at least one drawing executed in color. Copies of this patent or patent application publication with color drawing(s) will be provided by the Office upon request and payment of the necessary fee.

1. Two-part quick coupling device for electronic game steering wheels

1.1 : Perspective view from the front of a first part of the two-part quick coupling device for electronic game steering wheels.

1.2 : Back view of the first part of the two-part quick coupling device for electronic game steering wheels shown in 1.1.

1.3 : Side view of the first part of the two-part quick coupling device for electronic game steering wheels shown in 1.1.

1.4 : Rotated perspective view from the front of the first part of the two-part quick coupling device for electronic game steering wheels shown in 1.1.

1.5 : Perspective view from the back of the first part of the two-part quick coupling device for electronic game steering wheels shown in 1.1.

1.6 : Rotated perspective view from the back of the first part of the two-part quick coupling device for electronic game steering wheels shown in 1.1.

1.7 : Front view of the first part of the two-part quick coupling device for electronic game steering wheels shown in 1.1.

2.1 : Perspective view from the top of a second part of the two-part quick coupling device for electronic game steering wheels.

2.2 : Right view of the second part of the two-part quick coupling device for electronic game steering wheels shown in 2.1.

2.3 : Top view of the second part of the two-part quick coupling device for electronic game steering wheels shown in 2.1.

2.4 : Left view of the second part of the two-part quick coupling device for electronic game steering wheels shown in 2.1.

(Continued)

2.5 : Bottom view of the second part of the two-part quick coupling device for electronic game steering wheels shown in **2.1**.

2.6 : Front view of the second part of the two-part quick coupling device for electronic game steering wheels shown in **2.1**.

2.7 : Perspective view from the bottom of the second part of the two-part quick coupling device for electronic game steering wheels shown in **2.1**.

3.1 : Front view of the two-part quick coupling device for electronic game steering wheels.

3.2 : Bottom view of the two-part quick coupling device for electronic game steering wheels shown in **3.1**.

3.3 : Perspective view of the two-part quick coupling device for electronic game steering wheels shown in **3.1**.

3.4 : Side view of the two-part quick coupling device for electronic game steering wheels shown in **3.1**.

3.5 : Top view of the two-part quick coupling device for electronic game steering wheels shown in **3.1**.

3.6 : Perspective view from the bottom of the two-part quick coupling device for electronic game steering wheels shown in **3.1**.

3.7 : Perspective view from the top of the two-part quick coupling device for electronic game steering wheels shown in **3.1**.
